BRAIDED SLING

Vincent C. J. Peterson, Forty Fort, and Walter A. Loewen Wilkes-Barre, Pa., assignors to American Chain & Cable Company, Inc., Bridgeport, Conn., a corporation of New York

Application June 5, 1945, Serial No. 597,648

9 Claims.

(Cl. 87—8)

1

This invention relates to braided structures, and more particularly to slings, having a braided body portion with eyes formed at the ends to accommodate crane or hoist hooks with which the slings are used.

One of the purposes of utilizing braid is the prevention of twisting of the sling, such twist, in large sizes of slings, rendering it difficult for the workman to attach the eyes to the hoist hook.

Another purpose of braiding is to enable the manufacture of as flexible structure as possible, for ease in handling.

Prior types of braid, made with the above objects in mind, are usually difficult to fabricate, or entail a large number of splices.

It is therefore a primary object of the present invention to provide a method of braiding, and a braid, which will tend to prevent twisting of the sling under load.

It is a further object of the present invention to provide a braided sling with a minimum of splices.

It is a further object of the present invention to provide a braid which can be made by machinery if desired.

It is a further object of the present invention to provide a braid which is essentially round in cross-section and has equal flexibility in all directions.

Referring now to the drawings:

Fig. 1 shows an endless rope or strand, drawn as a solid element, folded upon itself to produce four double units or legs;

Fig. 2 shows the positions of the parts after completion of the first step of the braiding operation;

Figs. 3, 4, and 5 show the position of the parts after the second, third, and fourth steps in the braiding operation;

Figs. 6 and 7 show variations in the third and fourth steps;

Fig. 8 shows a completed sling produced according to the methods of Figs. 1 to 5.

Fig. 9 is an enlarged view of the braid produced by the method illustrated in Figs. 1-5; and

Fig. 10 shows the braid as produced by the method shown in Figs. 6 and 7.

The first step in producing the braid about to be described is the making of an endless rope 10, which can be accomplished by splicing or the use of a ferrule 11. By "rope" is meant, in this specification, a strand, rope proper, cable, braid, or even a solid element of suitable flexibility. The usual construction, however, is of wire rope.

The rope is then doubled or coiled to produce four double elements, as shown in Fig. 1, and seized at 12. The loops 13, 14, 15, and 16 form an eye, and the lower sections are to be braided. For the sake of clearness, the four doubled ropes are 60

2

shown as spread on four points of the compass, and labeled N, S, E, and W for purposes of this description. The individual ropes are labeled with subscripts 1 and 2.

5 The braiding operation consists of interchanging N with S, and E with W, alternately, until the required length of braid is produced. Two methods of accomplishing this are shown. That shown in Figs. 1 to 5 will be first described.

10 The first step is to pass the S double element through the N double element, and place the S double element in the position formerly occupied by the N element, and the N double element where the S double element was. This is shown in Fig. 2.

15 The second step is passing W through E, interchanging their positions, as shown in Fig. 3. After this, the N double element is passed through the S double element, as shown in Fig. 4, interchanging the positions of the N and S elements.

20 The fourth step is shown in Fig. 5 and consists of passing E through W and moving W to the west position and E to the east position. The parts are all now in the position they occupied at the start of the braiding operation, the steps of which are repeated until a sufficiency of braid has been produced.

25 The completed braid has an appearance as shown in Fig. 8, and the seizing at 21 holds it in place. The end eyes can be finished off by serving, or attachment of a thimble, or may be left as separate ropes.

30 The characteristic appearance of braid produced by the described method is that ropes N2 and S2 are helically twined around each other, as are N1 and S1, E1 and W1, E2 and W2. Ropes having the same letter for a name (e. g., N1, N2) pass between the ropes starting at right angles, at intervals, which constitutes the braiding necessary.

35 It is important to note that with the braiding carried on as described—i. e., by pairs of ropes connected together, the intertwining of one pair of ropes, as for example N1, S1, is accompanied by an exactly equal and opposite intertwining of the other pair N2 and S2. This automatically introduces what might be termed right and left lays, equal and opposite, and minimizes any tendency of the sling to twist under load.

40 In Figs. 6 and 7 a variation in method, producing a corresponding variation in braid structure, is shown. This variation consists of always passing one double element of a pair—e. g., the S and W units—through its opposite double element.

45 This is illustrated by starting the braid as before, from Figs. 1 to 3. As a third step, the S double element is passed through the N double element, and as a fourth step the W double element is passed through the E double element,

these steps being illustrated in Figs. 6 and 7 respectively.

A comparison of the two methods of braiding will bring out the distinctive feature of the construction of the form described in connection with Figs. 6 and 7. This difference is particularly evident in Figs. 9 and 10. In this form, the N and S ropes do not twine about each other, nor do the E and W ropes. On the contrary, the N ropes are always outside of the S ropes, and the E ropes are similarly always outside of the W ropes. Consequently, there is no twining of the N ropes around the S ropes, nor of the E ropes around the W ropes, which distinguishes the present structure from that of the first described form.

Thus, in Fig. 9 the rope E₁ passes over rope W₁ at the top of the page and passes under rope W₁ at the next crossing. This alternation in crossing is, in effect, a twining of rope E₁ around rope W₁ as described, and results from manufacture of a braid by the first method. The same is true of all the other corresponding pairs of ropes in the braid illustrated in Fig. 9.

The braid illustrated in Fig. 10 has had members straightened out so that the relationship of the ropes is more clearly evident. However, it does illustrate, even though somewhat diagrammatically, the relationship of the various parts of the braid as described in connection with Figs. 6 and 7. For instance, the rope E₂ is always on top of the rope W₂. Directly below W₂ lies rope W₁ in those parts of the braid which are farthest from the centerline of the drawing. Below the W₁ rope there lies the E₁ rope. The relation of the N and S ropes is quite obvious from the figures. Thus, any one rope could be considered as lying substantially in a plane and merely having a sinusoidal path which interlaces it with a pair of ropes which lie in planes 90° from the plane of the first-mentioned rope.

It is to be understood that the method described does not require the use of a single rope, nor the utilization of doubled legs as described, although these expedients are very advantageous in sling constructions, both from the point of view of convenience of construction and lack of splices, and that this invention is to be considered as having the scope of the appended claims, rather than that of the above illustrative disclosure.

We claim:

1. The method of braiding eight ropes which comprises arranging the ropes in four pairs, each pair occupying the corner of a quadrilateral, transposing the pairs of one diagonal, one pair passing between the ropes of the other pair, transposing the pairs of the other diagonal, one pair passing between the ropes of the other pair, and repeating until sufficient braid has been formed.

2. The method of braiding eight ropes which comprises arranging the ropes in four pairs, each pair occupying the corner of a quadrilateral, transposing the pairs of one diagonal; one pair passing between the ropes of the other pair, transposing the pairs of the other diagonal, one pair passing between the ropes of the other pair, and repeating until sufficient braid has been formed, the pair occupying two adjacent corners before each transposition passing between the ropes of their diagonally opposite pairs.

3. The method of braiding eight ropes which comprises arranging the ropes in four pairs, each

pair occupying the corner of a quadrilateral transposing the pairs of one diagonal, one pair passing between the ropes of the other pair, transposing the pairs of the other diagonal, one pair passing between the ropes of the other pair, and repeating until sufficient braid has been formed, the same pair of ropes on each diagonal always passing between the ropes of the other pair on that diagonal.

4. The method of braiding an eyed structure which comprises forming four loops of rope and arranging them on the corners of a quadrilateral, transposing the loops of one diagonal, transposing the loops of the other diagonal, and repeating until sufficient braid is formed, one of each pair of loops so transposed passing between the ropes of the other loop.

5. The method of braiding an eyed structure which comprises forming four loops of rope and arranging them on the corners of a quadrilateral, transposing the loops of one diagonal, transposing the loops of the other diagonal, and repeating until sufficient braid is formed, the loops occupying two adjacent corners before each transposition passing between the ropes of their diagonally opposite loops.

6. The method of braiding an eyed structure which comprises forming four loops of rope and arranging them on the corners of a quadrilateral, transposing the loops of one diagonal, transposing the loops of the other diagonal, and repeating until sufficient braid is formed, the same loop on each diagonal always passing between the ropes of the other loop on that diagonal.

7. A braid structure of eight ropes arranged in pairs, two pairs in opposed serpentine formation to form a plurality of loops, the other two pairs also in opposed serpentine formation approximately at right angles to the first mentioned two pairs and passing through the loops formed by the first-mentioned two pairs.

8. A braided structure of eight ropes arranged in pairs, two pairs in opposed serpentine formation, one pair thereof passing between the ropes of the other pair thereof, said two pairs defining a series of loops, the other two pairs in opposed serpentine formation, one pair thereof passing between the ropes of the other pair thereof, the last-mentioned pairs passing through the loops in the first-mentioned two pairs.

9. A braided structure of eight ropes arranged in pairs, two pairs in opposed serpentine formation, the ropes of one pair thereof passing alternately between and around the ropes of the other pair thereof, the other two pairs in opposed serpentine formation, the ropes of one pair thereof passing alternately between and around the ropes of the other pair thereof, the last-mentioned pairs passing through the loops in the first-mentioned two pairs.
